Patented Sept. 16, 1958

183,522

WASHING MITT

Bertha E. Jackman, Springfield, Ill.

Application January 4, 1957, Serial No. 44,402

Term of patent 14 years

(Cl. D9—2)

Fig. 1.

Fig. 2.

Fig. 1 is a perspective view of a washing mitt embodying my new design, shown positioned on a hand, with a portion of the arm shown in broken lines for illustrative purposes only; and Fig. 2 is a top plan view of the washing mitt.

I claim:

The ornamental design for a washing mitt, substantially as shown and described.
